(57) **CLAIM**

I claim the ornamental design for a fixing frame for liquid crystal display module, as shown and described.

DESCRIPTION

FIG. 1 is a top perspective view of a fixing frame for liquid crystal display module showing my new design;

FIG. 2 is a front elevational view thereof;

FIG. 3 is a rear elevational view thereof.

FIG. 4 is a left side elevational view thereof;

FIG. 5 is a right side elevational view thereof;

FIG. 6 is a top plan view thereof;

FIG. 7 is a bottom plan view thereof,

FIG. 8 is a bottom perspective view of a fixing frame for liquid crystal display module showing my new design; and, FIG. 9 is a front end view of the fixing frame for liquid crystal display module in accordance with my design, shown in its environment thereof.

The broken lines depict environmental subject matter that forms no part of the claimed design.

1 Claim, 7 Drawing Sheets
